UNITED STATES PATENT OFFICE.

BENJAMIN F. SHURZ, OF MARION, OHIO.

AUTOMATIC RAILWAY-BRAKE VALVE.

1,092,958.

Specification of Letters Patent. Patented Apr. 14, 1914.

Application filed February 27, 1913. Serial No. 751,081.

To all whom it may concern:

Be it known that I, BENJAMIN F. SHURZ, citizen of the United States, residing at Marion, in the county of Marion and State of Ohio, have invented certain new and useful Improvements in Automatic Railway-Brake Valves, of which the following is a specification.

This invention relates to automatic rail-way brake valves and has for its object to provide an improved device which is operated by a track obstacle or detent for the purpose of stopping a train on occasions of danger or otherwise.

The device includes a valve held closed by automatic means, against the train or brake pipe pressure, and which may be tripped to permit it to open under certain conditions and thereby bleed the brake pipe and allow the brakes to set.

A feature of the invention is that the valve and its seat and stem are located on the outside of an air chamber which is in communication with the brake pipe, so that the air pressure tends to open the valve instead of keeping it closed as in some other devices. This has the advantage that in case of an accident or any breakage or disarrangement of the valve mechanism, it will be opened by the pressure and thus automatically set the brakes.

A further feature of the invention is a secondary valve which may be operated under certain conditions such as the inoperativeness of the main valve for any reason.

The invention will be more fully understood from the following specification and the accompanying drawings.

In the drawings Figure 1 is a side elevation illustrating a convenient means of supporting the valve structure, on the truck of an engine or the like. Fig. 2 is a vertical section of the valve and its casing. Fig. 3 is a vertical section illustrating the secondary valve in closed position. Fig. 4 is a view similar to Fig. 3, with the secondary valve open.

Fig. 1 illustrates the valve casing 20 carried on the truck, and a track device or detent 7, located beside the rail. The details of this detent are immaterial, and it may form the subject of an other application,

but it may be remarked that it contains an incline up which the valve operating device rides when the detent is raised to operative position. The valve casing 20 has a chamber A at the top which is connected by a suitable pipe 40 to any part of the brake pipe (not shown) so that the pressure in the chamber A is the same as that in the brake pipe. A partition 41 extends across the casing and separates the chamber A from the chamber B which has an outlet or exhaust 42 to atmosphere. The partition 41 has therein a valve seat 22 with which operates the valve 21, which is subjected to the pressure in the chamber A, tending to open the same. The stem 23 of the valve extends downwardly through partitions 43 and 44, which form guides, and at its lower end has a block 24 with an inclined slot or opening 24^a through the same. Fitting through this slot is a double wedge key 25, with heads 25^a to retain it in place, and this key may work through the slot for the purpose of raising or lowering the valve. The key is confined between the partition 44 and a lower partition 45, and the outer ends of the heads 25^a are beveled as indicated at 25^b.

A vertically movable trip rod 26 is supported and guided in the casing, its lower end extending through the bottom of the casing and being provided with a roller 32 adapted to strike the detent 7 or the like, for the purpose of forcing the rod upwardly. The head of this rod is beveled as indicated at 26^a and is located in position to strike the bevel 25^b at the corresponding end of the key 25, and when the rod is pushed up it forces the key toward the left (in Fig. 2) thereby pulling down the valve 21 and opening the same, this action being assisted by the air brake pressure in the chamber A. The result is to bleed the brake pipe and set the brakes.

The valve 21 may be reset or closed by means of a vertically movable rod 27 having an inclined head 27^a which bears against the opposite end of the wedge key. The rods 26 and 27 are connected by a lever 28 pivoted at the middle, and one end working in the slot 26^b in the rod 26, so that when the rod 26 drops or is pulled down the rod

27 is pushed up and the key 25 is shifted to the right and by its wedge action lifts and closes the valve 21.

A detent 30 is pivoted at 50 to a suitable support 51 in the casing, and is adapted to engage in one of the notches 29 in the rod 26 so as to hold said rod in raised position until released, which release may be effected by pulling a rod 31 extended by suitable connections to the cab, or otherwise located in available position for operation. It will be seen that when the rod 26 is lowered or let down the key 25 is shifted to close the valve 21, and it will remain closed until the wedge key 25 is shifted to the left, as by the lift of the rod 26 incident to striking a track device. This lift will by the means described open the valve and set the brakes.

It is possible that owing to high speed of the train or other reasons the rod 26, when it strikes the tripper or track device, might not lift, and in order to set the brakes under such circumstances I provide a secondary valve shown particularly in Figs. 3 and 4. This valve 33 closes against the top of a tubular outlet 60 leading from the chamber A to the chamber B, and it may be lifted to open the same by means of a rod 36, the upper end of which carries said valve and the lower end of which has a rounded head 35 which rests in a cavity 61 in a bottom plate 62 attached to the bottom 34 of the casing 20. The head 35 extends through an opening in said bottom 34. The second or double bottom plate 62 is attached to the bottom 34 by means of small bolts 63 or some similar devices which under sufficient impact will break and allow the secondary bottom plate 62 to be knocked or shifted laterally, as indicated in Fig. 4. The rod 26 extends through an elongated slot 34^a in the bottom 34, but fits rather closely through an opening at 64 in the lower plate 62.

In the event of an impact against the roller 32 with such suddenness or at such high speed as not to permit the rod to lift, the lateral strain or shock of the impact will be applied to the bottom plate 62, with the effect that the bolts 63 will be sheared or broken and the lateral movement of the plate 62 will cause the head 35 to ride up out of the depression 61, thereby lifting the stem 36 and the valve 33 and opening the same, permitting the train pipe pressure to bleed through the tubular part 60 and thus set the brakes. Under ordinary conditions the main valve 21 will be operated by lift of the rod 26, the secondary valve being actuated only in the event that the main valve devices cannot operate in the manner described, for the causes referred to or other extraordinary circumstances. It will be noted that when the valve 21 is closed, it is

locked closed, until the rod 26 is operated, and after it is opened it stays opened, with the brakes set, until it is again set or closed by manual operation.

What I claim as new is:

1. In a device for setting air brakes, the combination of a casing, a valve therein controlling an exhaust opening from the brake pipe and provided with a stem having an inclined slot, a wedge key slidable crosswise in said slot and adapted to thereby move the valve to open or closed position, and a reciprocating trip operated rod having an inclined head bearing against the key and adapted to shift the same. 70

2. In a device for setting air brakes, the combination of a casing, a valve therein controlling exhaust from the brake pipe, and provided with a stem having an inclined slot, a wedge key shiftable crosswise in said slot, to open or close the valve, a pair of oppositely moving rods with inclined ends bearing against opposite ends of said key and acting to shift said key in opposite directions, and a lever between the rods, one of said rods projecting beyond the casing in position to strike and be moved by a track device. 80

3. In a device for setting air brakes, the combination of a casing, a valve therein controlling exhaust from the brake pipe, and provided with a stem having an inclined slot, a wedge key shiftable crosswise in said slot, to open or close the valve, a pair of oppositely moving rods with inclined ends bearing against opposite ends of said key, and acting to shift said key in opposite directions, and a lever between the rods, one of said rods projecting beyond the casing in position to strike and be moved by a track device and a manually released catch engageable with one of said rods to hold the same in the position to which it is moved by said device. 95

4. In a device for setting air brakes, the combination with a casing having a chamber under brake pipe pressure, primary and secondary valves controlling exhaust from said chamber, an impact actuated device to open said primary valve by ordinary impact against a track obstacle, and breakable means operatively connected to the secondary valve and to said device, to open the secondary valve by extraordinary impact of said device against the track obstacle. 110

5. In a device for setting air brakes, the combination with a casing having a chamber under brake pipe pressure, primary and secondary valves controlling exhaust from said chamber, a longitudinally slid able impact actuated rod operatively connected to said primary valve to open the same, a 115 plate mounted on the casing adapted to be 120

125

moved by lateral movement of the rod, breakable fastenings between said plate and the casing, adapted to be broken by excessive impact against the rod, to permit movement of the plate, and means actuated by said movement of the plate to open the secondary valve.

In testimony whereof, I do affix my signature in presence of two witnesses.

BENJAMIN F. SHURZ.
